CASING FOR STRIP MATERIAL FEEDER FOR ATTACHMENT TO SEWING MACHINES OR THE LIKE

Merton A. Sigoda, Brooklyn, N. Y., assignor to
Man-Sew Corporation, New York, N. Y., a cor-
poration of New York

Application May 8, 1950, Serial No. 9,778

Term of patent 14 years

(Cl. D70—2)

To all whom it may concern:

Be it known, that I, Merton A. Sigoda, a citizen of the United States, residing at Brooklyn, New York, in the county of Kings and State of New York, have invented a new, original, and ornamental Design for a Casing for Strip Material Feeder for Attachment to Sewing Machines or the like, of which the following is a specification, reference being had to the accompanying drawing, forming a part hereof.

Fig. 1 is a front perspective view taken from one side showing my new design for a casing for

strip material feeder for attachment to sewing machines or the like;

Fig. 2 is a rear perspective view taken from the other side.

I claim:

The ornamental design for a casing for strip material feeder for attachment to sewing machines or the like, substantially as shown.

MERTON A. SIGODA.
